UNITED STATES PATENT OFFICE.

CHARLES J. NEFF, OF SANDUSKY, OHIO.

TOY VEHICLE.

Application filed September 11, 1922. Serial No. 587,497.

To all whom it may concern:

Be it known that I, CHARLES J. NEFF, a citizen of the United States, residing at Sandusky, in the county of Erie and State 5 of Ohio, have invented certain new and useful Improvements in Toy Vehicles, of which the following is a specification.

The present invention relates to certain new and useful improvements in toy vehicles or wheeled toys, and has for its object to provide a device of this character which embodies novel features of construction whereby any selected one of a series of toy bodies of different types can be mounted 10 upon the supporting frame, thereby changing the character and appearance of the toy.

It is contemplated to provide a number of toy bodies which are of different designs and can be applied interchangeably to a 20 standard supporting frame or base. For instance, with a supporting frame or base for a toy automobile there may be different designs of toy bodies simulating trucks, stages, coaches, pleasure cars and the like, all of which are adapted to be interchangeably applied to the base, and the child can change the character of the toy automobile at will by mounting different toy bodies upon the supporting frame.

There may also be different forms of supporting frames, and if the supporting frame should happen to be for a toy railroad car the interchangeable body would be of such a character that the car could be 30 formed at will into a freight car, passenger car, stock car or the like. The invention has an almost unlimited range of adaptability, and in making the change the child is called upon to manipulate or mechanically adjust certain of the parts, and this is 40 a feature which tends additionally to amuse the child and accordingly enhances the value of the toy.

With the foregoing and other objects in 45 view the invention consists in certain combinations and arrangements of the parts as will more fully appear as the description proceeds, the novel features thereof being pointed out in the appended claims.

For a full understanding of certain specific embodiments of the invention reference is to be had to the following description and accompanying drawings, in which,

Figure 1 is a side elevation of a toy automobile which is constructed in accordance

with the invention and has a toy truck body applied to the supporting frame.

Figure 2 is a bottom plan view of the construction shown by Figure 1.

Figure 3 is a longitudinal sectional view 60 through the rear end of the toy taken on the line 3—3 of Figure 2.

Figure 4 is an enlarged detail perspective view of the seat.

Figure 5 is a longitudinal sectional view 65 through the toy showing another form of toy body as substituted for the toy truck body, the forward end of the toy being broken away.

Figure 6 is a detail view of one end of the 70 seat, showing a modified construction thereof.

Figure 7 is a transverse sectional view taken on a line corresponding to the line 7—7 of Figure 5, and showing the modification illustrated by Figure 6. 75

Figure 8 is a perspective view showing a still further modification.

Figure 9 is a side elevation of a toy railroad car embodying the invention, a portion 80 of one corner of the car being broken away and shown in section.

Figure 10 is a bottom plan view of the toy freight car body which appears in Figure 9, the body being detached from the supporting frame. 85

Figure 11 is a top plan view of the supporting frame of the toy railroad car.

Corresponding and like parts are referred to in the following description and indicated on all of the views of the drawings by 90 like reference characters.

Referring to Figures 1 to 7 of the drawings, the reference character A designates the supporting frame of a toy automobile. 95 This supporting frame is mounted upon the front running wheels 1 and rear running wheels 2, and is shown as provided with conventional mud guards 3 and running boards 4. The front axle 5 is pivoted at 6 100 so that it can be set at an angle when it is desired to adjust the toy for running in a circle.

So far as the present invention is concerned it is immaterial whether or not the 105 toy automobile is provided with any kind of a driving means. As illustrated on the drawings, however, the axle 7 of the rear running wheels is provided with a gear wheel 8 which meshes with a pinion 9 on a 110

countershaft 10, said countershaft being in turn provided with a gear wheel 11 meshing with a second pinion 12 on a shaft 13 which is provided with an inertia wheel 14. This is a conventional and well known form of inertia wheel toy in which the inertia wheel is positively connected by spur gearing to the driving wheels, the inertia wheel being started in motion by forcibly moving the toy 10 with the running wheels in engagement with a suitable surface, after which the toy is released and motion is transmitted from the inertia wheel to the driving wheels to propel the toy. Any other form of power means 15 may be substituted, or the supporting frame may be constructed entirely without any power means.

The top of the supporting frame A has an extended and substantially flat surface B at 20 the rear end thereof, as shown quite clearly by Figure 8, and the front of the frame may be provided with a toy radiator and hood cover construction, as indicated at 15. The seat 16 extends transversely of the supporting frame, being provided at its ends with downwardly extending ears 17 which are received within positioning slits 18 which are formed in the top of the supporting frame at opposite sides thereof. Also, as 25 indicated quite clearly by Figure 4, the back of the seat is provided at the upper edge thereof with a returned flange or hooked edge portion 19. A plate 20 at the bottom 30 of the seat 16 is so arranged as to fit directly against the top of the supporting frame A, and is formed with a rearwardly opening notch 22 which is adapted to register with a longitudinal slot 23 in the supporting frame and cooperate with a headed bolt 24 to lock 35 the seat removably in position.

The bolt 24 is slideable back and forth in the slot 23 and is shown as provided at the bottom of the supporting frame with a wing nut 25 which can be conveniently grasped 40 when it is desired to tighten or loosen the bolt. When the bolt is loosened and moved rearwardly in the slot 23 the head thereof is disengaged from the plate 20 at the base of the seat 16, so that the seat can be lifted out of position. On the other hand when the bolt is moved to the forward end of the slot 23 and tightened so that the side portions of the notch 22 are gripped by the head of the bolt, the seat is clamped tightly in position. The mouth of the notch 22 is preferably 45 flared, as indicated on the drawings, to facilitate the movement of the bolt into the notch, and it will be understood that any conventional type of bolt or fastening member 50 may be substituted for the particular form of bolt which has been illustrated and described.

A series of toy bodies are adapted to be 55 used interchangeably upon the supporting frame. The toy body C of Figures 1 and 3

simulates the body of a motor truck, while the toy body D of Figure 5 simulates the body of a stage or passenger car. Many other styles of toy bodies may also be used, and any selected one of the bodies may 60 be applied to the supporting frame and the character of the toy vehicle thereby completely transformed at will. The toy bodies C and D are each provided at their rear ends with transversely disposed depending flanges 65 26, which have the ends thereof returned at 26^a so that they will hook over a depending lip 27 at the rear end of the supporting frame. The forward ends of the toy bodies are engaged by the seat 16 so that any one of the 70 toy bodies is securely locked in position upon the supporting frame when it is applied thereto. The hooked upper edge portion 19 of the seat 16 fits over an edge portion of the toy truck body C, as indicated quite clearly by Figure 3, and the front of the toy body D may be provided with a lip to interlock with the hooked edge portion of the seat. It will thus be 75 obvious that when the toy body has been applied to the supporting frame and the seat clamped in position by the bolt 24, the toy body is securely fastened to the supporting frame so that it is not liable to be displaced thereon when handling the toy. 80 The toy body D is shown as formed with a forward extension d including side plates which receive the seat 16 between the same. These side plates are shown as formed with 85 depending ears 28 which project into the positioning slits 18 of the supporting frame and cooperate therewith to assist in holding the parts in proper relative position.

Figures 6 and 7 illustrate a slight modification in which the necessity of using a 90 detachable fastening member such as the bolt 24 is eliminated. The depending ears 17 at the ends of the seat are formed with lateral projections or knobs 17^a which have 95 a yielding action and are adapted to cooperate with the edges of the slits 18 to provide a spring lock to hold the seat in position. The seat may be forcibly pressed into position or pulled out of position, although 100 when the seat is in place, as indicated by Figure 7, the projections 17^a will have a spring engagement with the edges of the slits 18 and cooperate therewith to prevent 105 accidental displacement of the seat.

A further modification is shown by Figure 8, in which the slot 23^b extends transversely of the supporting frame A. The toy body E, which simulates a truck body, is formed at one side thereof with depending hook members 29 adapted to engage openings 30 at one side of the supporting frame, while the other side of the body is formed with a plate 31 which fits against the top of the supporting frame and has a notch 32 therein corresponding to the beforementioned notch 22. 110

at the base of the seat. The bolt 24^b is substantially the same in construction as the bolt 24, and is movable back and forth in the slot 23^b. When the bolt is caused to engage the notch 32 of the plate 31, the toy body E is securely clamped in position upon the supporting frame, although when the bolt is loosened and moved to the inner end of the slot, so that it is disengaged from the notch 32, the toy body can be removed from the supporting frame.

It will be understood from the foregoing that the detachable and interchangeable bodies may have an unlimited range of design, and that these toy bodies may be interchangeably secured to the supporting frame in any suitable manner, although each toy body is of a suitable size and has a proper base so that it can be fitted upon the supporting frame and will in fact blend therewith and become an inherent part thereof, thereby completely transforming the appearance and character of the toy vehicle.

Figures 9, 10 and 11 illustrate a possible modification in which the invention is embodied in a toy railroad car. The supporting frame H of the car may be provided with the conventional wheeled trucks 40, and may or may not be mounted to travel upon toy rails 41. Many different bodies may be interchangeably mounted upon this supporting frame H and the car thereby transformed into a freight car, passenger car, tank car or the like. The bodies would all have a base adapted to fit squarely upon the seat at the top of the supporting frame H. The toy freight car body J, which is shown by Figures 9 and 10 for illustrative purposes, is provided at one end thereof with a depending hooked portion 42 engaging a lip 43 at the corresponding end of the supporting frame. The opposite end of the toy freight car body J is provided with a plate 44 which fits against the top of the supporting frame and has a notch 45 therein adapted to register with a slot 46 in the supporting frame. A clamping bolt 47 is slideable in this slot 46, so that it can be moved into and out of engagement with the notch 45 of the plate 44. This clamping bolt 47 operates, as in the previous instances, to cooperate with the hooked end 42 of the toy body to fasten the toy body securely in position upon the supporting frame.

The invention can be embodied in any form of toy vehicle or wheeled toy. The interchangeable bodies of different designs all have base portions which correspond to the seat at the top of the supporting frame and are adapted to fit thereon, so that the design of the toy body will blend or harmonize with the design of the supporting frame. Any suitable means may be provided for detachably securing the toy bodies in posi-

tion upon the supporting frames, and by changing the toy bodies the character of the toy can be completely changed. Different designs of toy bodies can be supplied at small cost, so that a child having a supporting frame can enlarge his outfit by adding different designs of bodies thereto from time to time. Not only is the complete transformation of the toy when a different body is mounted thereon extremely pleasing to the child, but the mechanical adjustment or manipulation which is necessary to make the change also tends to amuse the child and accordingly enhances the value of the toy.

Having thus described my invention what I claim as new and desire to secure by Letters Patent is,

1. A toy vehicle of the character described, including a main supporting chassis, a removable toy body adapted to rest thereon, a separate and removable seat also adapted to rest thereon, means for detachably securing one only of said last mentioned members to the chassis, and means on said member for detachably engaging the other member to hold it in position on the chassis.

2. A toy vehicle of the character described, including a main supporting chassis, a removable toy body adapted to rest thereon, a separate and removable seat also adapted to rest thereon, means for securing one only of said last mentioned members to the chassis, and a hook element on one of said members arranged to detachably interlock with the other of the said members and releasable by a movement of one of said members relative to the other member, said movement being prevented by the securing of one of the members to the chassis.

3. A toy vehicle of the character described, including a main supporting chassis, a removable toy body, a separate and removable seat, means for securing one only of said last mentioned members to the chassis, and a hook element structurally integral with said member and carried by the said member for detachably engaging the other member to hold it in position on the chassis.

4. A toy vehicle of the character described, including a main supporting chassis, a removable toy body adapted to rest thereon, a separate and removable seat also adapted to rest thereon, means for securing one only of said last mentioned members to the chassis, positioning means on one of said members for engaging the chassis, and a hook element on one of said members for engaging the other member, said hook element being releasable by a movement of one member relative to the other member and said movement being prevented when one of the members is secured to the chassis.

5. A toy vehicle including a main supporting frame, a fastening member slidably

- mounted upon and carried by the supporting frame, a removable toy body, and means cooperating with the fastening member in one of its positions to hold the body in position on the supporting frame, the body being released when the fastening member is moved to another position.
6. A toy vehicle including a main supporting frame, a fastening member slidably mounted thereon, a removable toy body, and a notched member associated with the toy body and cooperating with the fastening member to hold the toy body in position upon the supporting frame, the sliding movement of the fastening member enabling it to be shifted into and out of engagement with the notched member.
7. A toy vehicle of the character described, including a main supporting chassis, a removable toy body adapted to rest thereon, a separate and removable seat also adapted to rest thereon, means for securing the seat to the chassis, and means on the seat for detachably engaging the body to hold it in operative position on the chassis.
8. A toy vehicle of the character described, including a main supporting chassis, a removable toy body adapted to rest thereon, a separate and removable seat adapted to rest thereon, means for securing the seat to the chassis, and a hook member carried by the seat and opening toward the bottom thereof, said hook member being adapted to releasably engage the body to hold the latter in operative position upon the chassis.
9. A toy vehicle including a main supporting frame, a fastening member movably mounted thereon, a detachable toy body, and a detachable seat member having an interlocking connection with the toy body and adapted to be engaged by the fastening member to secure the toy body and seat member in position upon the supporting frame.
10. A toy vehicle including a main supporting frame, a removable toy body, a separate seat member adapted to engage the toy body, means for detachably securing the seat member to the supporting frame, and independent means for positioning the seat member upon the supporting frame.
11. A toy vehicle including a main supporting frame, a detachable toy body, a detachable seat member engaging the toy body, means for positioning the seat member on the supporting frame, and a locking member movably mounted upon the supporting frame and adapted to engage the seat member in one of its positions.
12. A toy vehicle including a main supporting frame, a detachable toy body, a seat member engaging the toy body and having a notched plate, and a locking member slidably mounted upon the supporting frame and movable into and out of engagement with the said notched plate of the seat member.
13. A toy vehicle including a main supporting frame, a detachable toy body, a seat member engaging the toy body and formed with a notched plate, positioning means upon the seat member for engagement with the supporting frame, and a locking member slidably mounted upon the supporting frame and movable into and out of engagement with the notched plate of the seat member.
14. A toy vehicle including a main supporting frame, a detachable toy body, a seat member formed with a hooked portion adapted to engage the toy body and having a notched plate at the base thereof, and a fastening member movably mounted upon the supporting frame and shiftable into and out of engagement with the notched plate.
15. A toy vehicle including a main supporting frame, a detachable toy body, a seat member formed with a hooked portion adapted to engage the toy body and having a notched plate at the base thereof, positioning means for centering the seat member upon the supporting frame, and a fastening member movably mounted upon the supporting frame and shiftable into and out of engagement with the notched plate of the seat member.
16. A toy vehicle including a main supporting frame, a detachable toy body, a seat member formed with a hooked portion adapted to engage the toy body, means for centering the seat member upon the supporting frame, and a fastening member movably mounted upon the supporting frame and shiftable into and out of engagement with the seat member.
17. A toy vehicle including a main supporting frame, a detachable toy body, hook means for interlocking one end of the toy body with the supporting frame, a separate seat member formed with a hook portion adapted to engage the opposite end of the toy body, and a fastening member movably mounted upon the supporting frame and shiftable into and out of engagement with the seat member.
18. A toy vehicle including a main supporting frame, a detachable toy body, hook means for interlocking one end of the toy body with the supporting frame, a separate seat member formed with a hook portion adapted to engage the opposite end of the toy body and formed with a slotted plate, and a locking bolt slidably mounted upon the supporting frame and movable into and out of engagement with the notched plate of the seat member.
19. A toy vehicle including a main supporting frame having openings therein, a detachable toy body, hook means detachably connecting one end of the toy body to the

- supporting frame, a separate seat member formed with a hook portion adapted to engage the opposite end of the toy body and also formed with a notched plate, position- 5 35
5 ears carried by the seat member and adapted to engage the before mentioned openings of the supporting frame, and a locking member slidable upon the supporting frame and shiftable into and out of engagement with the notched plate of the seat member. 10 40
20. A toy vehicle including a main sup- porting frame, a detachable toy body, hook means detachably connecting one end of the toy body to the supporting frame, a plate associated with the opposite end of the supporting frame, and a fastening member movably mounted upon and carried by the supporting frame and shiftable into and out 15 45 of engagement with the said plate. 20 50
21. A toy vehicle including a main sup- porting frame, a detachable toy body, hook means detachably connecting one end of the toy body to the supporting frame, a notched plate associated with opposite end of the toy body, and a fastening member slidably mounted upon the supporting frame and movable into and out of engagement with 25 55 the notched plate. 30 60
22. A toy vehicle including a main sup- porting frame, a detachable toy body, means for securing an interlocking connection between one end of the toy body and the sup- porting frame, positioning means at the op- 35 65
posite end of the toy body for centering the toy body on the supporting frame, a detach- able seat member engaging the toy body, and means for fastening the seat member to the supporting frame. 40
23. A toy vehicle of the character de- scribed, including a main supporting chassis, a detachable toy body, means at one end of the toy body for obtaining an interlocking connection with the chassis, a separate seat member provided with structurally integral means for detachably engaging the opposite end of the toy body, and means for detach- ably securing the seat member to the chassis. 45
24. A toy vehicle including a chassis pro- vided with a substantially flat body receiv- ing seat and formed at the front thereof with imitation dash and engine hood, a se- ries of interchangeable bodies which are of different designs and are each provided a 50 65 base portion adapted to fit on said body receiving seat of the chassis, the design of each of the bodies being adapted to har- monize with the chassis and imitation hood to produce a toy vehicle of one particular kind, and quickly releasable fastening means for securing any selected one of the inter- changeable bodies to the chassis whereby a child can quickly make the change while playing with the toy. 60 65

In testimony whereof I affix my signature.

CHARLES J. NEFF.
